ABRADING APPARATUS

Walter L. Keefer, Hagerstown, Md., assignor to
Pangborn Corporation, Hagerstown, Md., a corporation of Maryland

Application October 13, 1937, Serial No. 168,799

18 Claims. (Cl. 51—9)

The present invention relates to abrading apparatus and it is more particularly concerned with apparatus for mechanically picking up abrasive and centrifugally discharging it at abrading velocities in any desired direction to surface clean castings and other articles of work.

Abrading machines are in use today embodying bladed rotors for propelling abrasive, wherein in the abrasive is fed over the inner end of the blades and they require the use of an impeller and impeller cage for securing proper directional control of the propelled abrasive. Although these machines are successful from a commercial standpoint they are not perfectly satisfactory because the impeller and impeller cage add a complication and also are further elements to wear out and require replacement. Impeller machines also require more power to operate them by reason of the frictional loss in churning the abrasive within the impeller cage.

Also machines are known to the art in which no impeller or impeller cage is used, but in all cases in such machines the abrasive feeds across the sides of the blades and not to the inner ends as in the present invention. Feeding over the sides of the blades so "blocks" or interrupts the flow of the abrasive from the feed spout that such wheels are relatively inefficient due to the large percentage of "splashed" abrasive and can only be fed in small quantities, not suitable for production demands.

It is accordingly the primary object of this invention to provide an abrasive propelling machine capable of throwing abrasive in any desired direction and yet which does not require the use of an impeller and impeller cage for feeding abrasive to the blades.

It is a further object to provide an abrading machine having a gravity abrasive feed device in combination with a rotor designed to effect discharge of the abrasive from the rotor in the desired direction.

Another important object is to provide an abrasive propelling rotor having blades which retard movement of the abrasive thereover so as to predetermine the direction in which the abrasive is discharged from the rotor.

My invention also aims to provide a novel mechanism for releasably holding the blades of an abrasive propelling rotor in place and which securely maintains them in proper position during operation and yet which may be readily operated to release the blades for replacement when desired.

Another object is to provide a centrifugal

abrading machine which will operate at a lower speed but will develop the same final abrading velocity as a machine having radial throwing blades.

A further object is to provide novel abrasive propelling blades for use with rotors of centrifugal abrading machines.

It is another object to provide novel blades for use in abrading machines and embodying a surface designed to retard outward movement of the abrasive thereover, the blade having a pocket thereon adapted to gather or concentrate the abrasive before it is propelled by the retarding surface of the blade.

This application is a continuation-in-part of my copending application Serial No. 33,185, filed July 25, 1935, now Patent No. 2,108,005 and further objects of the invention will become apparent as the specification thereof proceeds in connection with the annexed drawings, and from the appended claims. In the drawings:

Figure 1 is a vertical sectional view of one form of apparatus embodying the invention and shows the feeding device mounted in cooperating relationship with the rotor.

Figure 2 is a sectional view taken on the line 2—2 of Figure 1, looking in the direction of the arrows.

Figure 3 is an end elevational view of another form of machine embodying the invention and parts have been broken away to show the construction.

Figure 4 is a vertical sectional view of the machine shown in Figure 3 but the spout and cage have been shown in elevation in order to clarify the illustration.

Figure 5 is a fragmental top plan view of the face plate employed in the machine shown in Figures 3 and 4.

Figure 6 is a vertical fragmental sectional view illustrating the outer edge of the rotor and shows one form of vane locking ring that may be used in the machine.

Figure 7 is a view similar to Figure 6 but illustrates a modified form of locking means for the vanes.

Figure 8 is a fragmental face view of the rotor employed in the machine and illustrates one blade mounted thereon and shows a portion of the feed cage in section.

Figure 9 is a view looking at the outer end of the blade shown in Figure 8.

Figure 10 is a top plan view of the blade shown in Figure 8.

Figure 11 is a side elevational view of a modi-

fied form of blade and which may be used in the machine previously described.

Figure 12 is a side elevational view of a further modified form of blade, together with a guard or baffle cooperating therewith.

Figure 13 is a side elevational view of a still further modified form of blade, and

Figure 14 is a side elevational view of another modified form of blade together with a baffle co-operating therewith.

With continued reference to the drawings, wherein like reference characters have been employed to designate like parts throughout the several views thereof, and with particular reference to Figures 1 and 2, I have somewhat diagrammatically illustrated one form of abrasive propelling wheel embodying the invention, and the component parts will be taken up separately.

A rotor 10 is supported on a shaft 11 and the latter is carried by bearings in any suitable manner. One or more blades may be mounted upon rotor 10, but in the present instance I have shown four blades 12 as being carried by the rotor, each blade having a short, substantially radially disposed surface 13 and a long propelling surface 14 of preferably curved configuration. Each blade is preferably rounded at its inner end at 15, to reduce the abrasive blocking action of the blades as they pass the discharge opening in the feed mechanism, and each blade is also provided with an abrasive retaining flange 16.

Supported for adjustable rocking movement in any suitable manner adjacent the rotor is a feeding device 18, which is of generally cylindrical form and extends into the central space between the inner ends of the blades, and it is provided with an outer cylindrical surface 19; an abrasive feeding passage 21 having a mouth 22 terminating adjacent the inner ends of the blades; and a spout 23 into which the abrasive may be fed by any suitable mechanism.

The machine accordingly embodies no impeller and the abrasive may gravitate freely down through spout 23 and be picked up by the inner ends of the blades. Assuming that the rotor is operating at the desired speed (preferably from 2000 to 2500 R. P. M.), and that spout 23 is supplied with abrasive, the latter gravitates through passage 21 and on through the inner ends of blades 12, and by reason of the substantially radial disposition of surface 13 of each blade the abrasive is picked up with a minimum of "backwash" and splash, and is given an initial outward acceleration.

When the abrasive reaches curved surface 14 of each blade it is subjected to an accelerating influence of smaller magnitude because, as seen in Figure 2, this part of the blade surface is disposed at an angle too, or is inclined outwardly and forwardly with respect to the direction of rotation of the rotor.

The effect of centrifugal force upon the abrasive is therefore counteracted by the inclination of surface 14 and abrasive accordingly travels more slowly over the blades than when radially or rearwardly inclined blades are used. The abrasive accordingly may be said to be "retarded," when the term is employed in a comparative sense using a radial bladed rotor as a standard.

It accordingly takes more time for the abrasive to travel outwardly over the blades, and advantage is taken of this fact to adjust the point of discharge of the machine by selecting the inclination of the blades to give the desired discharge. In other words, the feeding mechanism,

being of the gravity type, must always feed generally downwardly, and therefore the angle through which the abrasive is carried by the blades must be computed from the downward position as a starting point.

In the present instance the discharge from the rotor is seen to be horizontal, as at 24, or at a point about 180° from the point of admission of abrasive to the blades. It is of course understood that minor adjustments in the direction of the discharge may be effected by rockably adjusting feeding device 23 so as to properly adjust the point of admission of the abrasive to the blades.

Irrespective of the inclination of the blades in a particular installation, the abrasive is discharged from the blades at a speed which is substantially equal to the linear speed of the blade tips, and the abrasive discharge means takes a direction substantially tangential to the path of the blade tips, because the radial component of the final velocity has been "suppressed" or reduced by the forward inclination of the blades.

In Figure 2 the tip of each blade 12 is seen to be disposed at an angle α with respect to a radius r drawn through its inner edge, and it is to be understood that this angle may be increased or decreased depending upon whether it is desired to have the machine discharge at a greater or less distance from the point of admission of abrasive to the blades. Angle α may assume a wide variety of values, but its upper limit is determined by value at which the abrasive, after admission to the blades, will not be propelled outwardly thereon. This limiting value will vary with the type of abrasive used and the condition of the surfaces of the blades, and therefore is governed by the angle of repose of the particular abrasive used and upon the surface of the blade employed.

Although surface 14 has been illustrated as of curved concave configuration, it is to be understood that it may be of plain or convex shape or assume the forms of the subsequently described blades without departing from the spirit of the invention. A further important advantage secured by reducing the outward radial velocity of the abrasive resides in the fact that blade wear is materially reduced.

Referring now to the machine illustrated in Figures 3 to 10, inclusive, and with particular reference to Figures 3 and 4, the wheel is mounted within the housing having a rear plate 30 which is covered by the wear plate 31 and a front plate 32 which is in turn covered by a wear plate 33. The housing is mounted upon a base 34 in any well known manner.

A shaft 35 is journaled in bearings (not shown) and carries a flange 36 to which the rotor proper is secured by means of a plurality of screws 38.

Secured to rotor or head plate 37 by means of a central screw 39 and a plurality of screws 41 located adjacent the periphery of the head is a guide plate 42. As seen in Figure 5, plate 42 is provided with a plurality of non-radial slots 43, each of which terminates in a large end 44 which provides clearance for the inner ends of the blades. The side walls of slots 43 function as guides for the abrasive propelling blades and to this end they are provided with bevelled or inclined faces 45. The guides are preferably one thirty-second of an inch wider at their outer end than at their inner end in order to facilitate removal of the blades, especially when fine abra-

sive finds its way between the blades and guides. As indicated at 46 the plate may be cored out if desired to lighten it.

As best illustrated in Figure 9, a plurality of abrasive propelling blades B are associated with the rotor and they each are provided with a flat base 48 which abuts head plate 37. They are also provided with inclined side faces 49 and 51 which cooperate with inclined faces 45 of plate 42. The face 48 of the base of the blade is preferably disposed at approximately 88° with respect to the abrasive propelling face of the blade, and sufficient clearance is provided so that when the machine is in operation and the blades are placed under load they will rock into the position shown and dispose their abrasive propelling surfaces substantially normal to the face of the rotor. By proceeding in this manner sufficient clearance may be provided between the parts so as to allow the blades to be slid freely out of the machine and yet when the machine is in operation they will be disposed accurately in abrasive propelling position. The base of the blade is preferably so formed as to provide a recess 53 for a blade retaining spring (not shown).

As best seen in Figures 8 and 9, each blade is provided with an abrasive retaining flange 54, which is comparatively straight for the major part of the length of the blade, and which merges into a deeper retaining flange 55 at the inner end of the blade.

The inner extremity of the blade provides an abrasive propelling pick-up surface 56 which curves sharply back with respect to the direction of rotation of the rotor and merges with a curved gathering surface or pocket 57, and the latter in turn merges with a substantially straight abrasive propelling surface 58. As shown in Figure 8, the rear surface of the inner blade tips, designated as 56a, recedes so as to avoid contact with the severed end of the abrasive ribbon.

As the abrasive is fed on to the blade by the feeding means to be hereinafter described, surface 56 rapidly picks it up and in view of the rearward inclination of this surface the impact at the moment of pick-up is comparatively small. Just subsequent to pick-up the abrasive is "gathered" or concentrated on curved surface 57 and then starts to move outwardly comparatively slowly over straight surface 58. In view of the fact that in this form of wheel the abrasive is retained on the blades for approximately one revolution, if the abrasive were not "gathered" it would spread out during discharge so as to undesirably increase the discharge angle from the rotor. By providing a "pocketed" end on the blade the portion of the abrasive ribbon that is cut off is maintained substantially intact until it attains the main propelling surface 58.

60 Blade locking mechanism

The preferred form of blade retaining means is illustrated in Figure 6 and with continued reference to this figure, rotor 37 is provided with a plurality of short plugs 61 which are secured in place in the periphery of the rotor in any suitable manner. Mounted for axial sliding movement upon plugs 61 as bearings, is a comparatively massive locking ring 62, having an inclined abutment surface 63 and a radial abutment surface 64. Each blade B is provided at its outer end with an inclined surface 65 and it is preferably of frustro conical shape, so as to cooperate in full surface engagement with abutment wall 63.

The blades are removed from the apparatus simply by moving them inward a slight distance sufficient to allow the inner periphery of abutment surface 63 to clear the blades and ring 62 is then moved to the right into the dotted line 5 position. The blades may then be freely moved outwardly from their guides.

In view of this comparatively small bearing surface presented by plugs 61, any abrasive that finds its way between the ring and the periphery 10 of the rotor cannot set up a binding action and resist ring removal. Also, in order to reduce the amount of abrasive that rebounds between the parts, rotor 37 and ring 62 are provided with step formations 66 and 67 respectively. Therefore, 15 should stray abrasive in its movement outwardly toward the rear of plate 42 enter the space between rotor 37 and ring 62, it will be stopped, thereby preventing abrasion of plugs 61.

In Figure 7 I have shown a somewhat modified form of vane-holding device, but it possesses certain features in common with that just described because it embodies a ring 62a mounted on the periphery of rotor 37a and has an inclined abutment face 63a disposed in the path of movement of blades B'. Blades B' are provided with inclined outer ends 65a and ring 62a, rather than being slidably mounted upon the outer portion of the rotor, is provided with an annular flange 71 which seats in annular groove 72 in 30 the rotor.

The blades are removed in this form of the invention by moving them inwardly sufficiently to allow ring 62a to clear their outer ends and then the ring 62a is moved axially to the left 35 and completely removed from the machine. Blades B' may then be freely moved outwardly in their guides.

Feeding mechanism

Any desired form of feeding mechanism may 40 be employed to introduce abrasive over the inner ends of the blades but I prefer to employ the novel feed assembly shown in Figures 3, 4 and 8 as it has proven very satisfactory in service. The feeding device preferably comprises a generally cylindrical cage 75 which is disposed in the central space defined by the inner ends of blades B and it is provided with a plurality of rebound surfaces 76 for a purpose that will presently appear.

Cage 75 terminates in a flange 77 and is secured, by means of studs and nuts, to a member having a flange 78. The assembly extends through aligned openings in wall 32 of the housing and liner 33.

As seen in Figure 3 the opposite sides of flange 78 are enlarged to provide for the formation of a pair of arcuate slots 79 and 81, a pair of studs 82 are secured to wall 32 and extend through openings 79 and 81. By turning a pair of nuts 83 on studs 82 it is apparent that cage 75 may be secured to casing 32 in any desired adjusted position within the range of movement permitted by slots 79 and 81.

Preferably, though not necessarily formed integrally with cage 75, is a diagonally disposed feed conduit 85 which as seen in Figure 3 is substantially bisected by a diametrical plane passing through the cage and yet, in Figure 4 it is observed to be disposed diagonally or at an angle of approximately 45° with the axis of the mechanism. The lower end of feed conduit 85 terminates in an opening 86 which is observed to incline outwardly and forwardly with respect 75

to the direction of rotation of the rotor and is provided with a sharply curved forward wall 87 and a less sharply curved rearward wall 88.

Abrasive is introduced into feed conduit 85 by means of a spout 89 having a pair of lugs 91 secured to housing sidewall 32 by means of a pair of cap screws 92.

As seen in Figures 3 and 4 the lower end of spout 89 is tapered and the upper end of conduit 85 assumes a hopper-like form so that the cage may undergo a small range of adjustment without interference from spout 89. Abrasive is preferably admitted to the upper end of spout 89 by means of a metering mechanism in order 10 to provide a uniform blasting action and this mechanism may assume any suitable form well known in the art.

It is accordingly apparent that when the machine is brought up to operating speed; for 20 instance, speeds ranging from 2000 to 2500 R. P. M., and abrasive is fed through spout 89, it flows into conduit 85 and in issuing from opening 86 it is promptly picked up by the inner ends of the blades B, which pass fairly close 25 to the feed opening.

The abrasive that is properly picked up by the blades moves outwardly over the surfaces of the blades and is discharged from the wheel in the manner previously described. In view of the 30 fact that as a practical matter it is impossible to perfectly pick up all of the abrasive issuing from slot 86, surfaces 16 are employed to rebound back toward the discharge opening any abrasive that may strike the inner extremity of the blades 35 and ricochet toward the cage.

In other words, the stream of abrasive issuing from opening 86 may be regarded as a continuous abrasive ribbon and if it were possible to employ a blade that would maintain continuously a very sharp pick-up edge, then practically all of the abrasive would be properly picked up. However, as a practical matter, it is impossible to maintain a sharp edge on the inner ends of the blades and applicant has accordingly provided rebound surfaces for compensating for the action of the comparatively "dull" blades that must be used in practice. For instance, if a cage having a smooth cylindrical surface were used, and an abrasive particle 50 was struck by the inner end of the blade so as to ricochet toward the cage, it would leave the cage at an angle of reflection equal to the angle of incidence and would again be picked up by the blade at a point angularly remote from the proper pick-up zone adjacent opening 86. By providing surfaces 16 they cause the ricocheting abrasive to be thrown back toward the pick-up zone and hence cause them to be picked up in the proper angular position. Otherwise, an angularly delayed pick-up of the abrasive would effect a similar angularly delayed discharge of the stray abrasive, which would occur beyond the useful range of the wheel and would not strike the work, and would probably abrade the cabinet or other stationary parts of the machine.

With the form of blade illustrated in Figures 8, 9 and 10, I have found that when the wheel is fed with abrasive downwardly as seen in Figures 3 and 4, the abrasive is retained in the wheel substantially a whole revolution and is discharged downwardly. In other words, the wheel may be said to possess a one-hundred per cent degree of retardation, because the abrasive is discharged from the same angular portion of 70 the rotor as it is admitted to the blades. It is

accordingly apparent that by reason of the feed mechanism and blade design of my machine, I am able to provide a blast wheel having directional control and which is operable to blast downwardly and yet it is not necessary to employ an impeller because the abrasive is fed downwardly by gravity.

Blade design

The exact dimensions and proportions of the 10 various parts of the blade may vary somewhat depending upon the particular characteristics desired and the degree of retardation of delivery of the abrasive which is to be effected.

Referring particularly to Figure 8, this shows 15 a so-called one-hundred per cent retarding vane, and it is so termed because it is so shaped as to require substantially a full revolution of the rotor to discharge the abrasive from it. The axis of rotation of the wheel is indicated at C and it 20 will be observed that a radius R_1 passing through the center C and the innermost end of straight surface 58 makes an angle of approximately 57° with respect to surface 58. It is to be understood that applicant is not limited to 25 this particular angle, but that it may be increased or decreased to vary the characteristics of the machine desired. It is also observed that straight surface 58 which inclines rearwardly with respect to the direction of rotation makes 30 an angle of approximately 13° with respect to a radius R_2 passing through the center C. It is also seen that the inner surface 58a of the inner end of the blade makes an angle of approximately 35 30° with respect to surface 58 of the 35 blade.

The blades of the present invention incline outwardly and forwardly with the result that the final or discharge velocity, which they impart to the abrasive, is higher than in a radial-bladed machine of comparable size when operated at the same speed. The increase in velocity is dependent upon the degree of forward inclination of the blades, the greater the inclination the greater the final velocity.

For instance I have found that when the rotor is provided with the form of blade shown in Figure 8, and wherein the propelling surface 58 makes an angle of 25° to a radius passing through the blade tip, the rotor need be operated 50 at only 93 per cent of the velocity required in a radial bladed rotor to develop the same abrading efficiency.

Referring to Figure 8, the abrasive moving outwardly over the tip of surface 58 possesses an outward velocity component V_o and a tangential or forward velocity component V_f and completing the parallelogram, the final or resultant velocity V_r is shown. Also shown, in this figure, is the velocity diagram for a radial blade having 60 the same speed of rotation and it is observed that although V_o' is slightly greater than V_o , the diagram assumes the form of a rectangle and the final or resultant velocity V_r' is lower than V_r for the forwardly inclined retarding blade. 65

Referring now to Figure 11 of the drawings, I have illustrated a somewhat modified form of blade which possesses a somewhat less degree of retardation than the blades just described.

With continued reference to this figure, the 70 blade comprises a base or web portion 101 terminating in a pair of ears 102 which are provided with curved slots 103. The blade is clamped to rotor 31 by means of a pair of cap screws 104, and by reason of the elongated slots 103 the blade 75

may be secured to the rotor in a plurality of adjusted angular positions.

The blade is provided with a comparatively straight abrasive pick-up surface 105 which inclines slightly rearwardly with respect to the direction of rotation and it smoothly merges with a straight abrasive propelling surface 106. The blade is provided with an abrasive retaining flange 107 at its free edge and with a somewhat higher abrasive flange 108 at its inner edge for protecting the rotor against wear.

It is accordingly apparent that when this blade is used the abrasive will be picked up by surface 105 somewhat less rapidly than in the form of blade shown in Figure 8 and that it will be propelled outwardly over surface 106 and discharged from the wheel as described in the other forms of the invention. Also, by loosening screws 104 the blade may be rocked to present its propelling surface 106 at a different angle or as to possess a different degree of retardation. The abrasive may be fed to this blade in the same manner as that described in connection with the previously illustrated forms of the invention.

In Figure 12 I have shown a further modified form of blade embodying a web portion 101a and having lugs 102a for securing it to the rotor, and is secured to the rotor by means of cap screws as previously described. This blade embodies a straight pick-up surface 110 which is rearwardly inclined with respect to the direction of rotation of the rotor and it is disposed approximately normal to a long propelling surface 111 of the blade. Surfaces 110 and 111 are joined by a smoothly curved portion 112 which constitutes an abrasive-gathering pocket. This blade is also provided with an abrasive retaining flange 113.

In connection with this blade I have illustrated a guard or baffle member embodying a flat web portion 114 secured to the rotor by a pair of cap screws 115. The guard member is provided with an abrasive baffle surface 116 and at its free edge is provided with a flange 117.

It is accordingly seen that as the abrasive issues from opening 86 in cage 75 it will be picked up by surface 110 and gathered in pocket 112 and propelled outwardly over surface 111 and discharged from the rotor as previously described. Also, when the abrasive issues from the discharge opening in the cage a part of the ribbon that has been severed by the proceeding vane may be deposited on surface 116 and will find its way to propelling surface 111 by the time or shortly after pick-up surface 110 attains the discharge slot, thereby utilizing all of the abrasive issuing from the slot and insuring that it will be deposited on the blade at the proper point during rotation.

In Figure 13 there is disclosed a further modified form of blade embodying a comparatively straight pick-up surface 121, a straight propelling surface 122 and a smoothly curved surface 123 which connects surfaces 121 and 122. The junction with surfaces 123 and 121 defines a comparatively smooth pocket 124 for gathering the abrasive and surface 123 which constitutes a transition between the pocket and surface 122 effects a gradual increase of speed of the abrasive prior to the time the abrasive attains the inner end of surface 122.

In Figure 14 I have shown a blade having a straight pick-up surface 127 and a long propelling surface 128. Surfaces 127 and 128 are joined by a smoothly curved surface 129 and a surface 131 of comparatively short radius. Surface 127 inclines rearwardly with respect to the direction of

rotation of the rotor to a considerable degree with the result that the abrasive picked up by the inner ends of the blade comparatively rapidly attains the curved surface 131 and is then comparatively smoothly picked up on surface 129 prior to admission to surface 128.

In this form of the invention I have also shown a baffle member 132 having a vertical portion 133 and a horizontal portion 134. This baffle functions substantially in the same manner as that previously described, and in addition surface 134 prevents rebound of the abrasive upwardly from the abrasive propelling surface 128.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by the United States Letters Patent is:

1. In an abrading apparatus, a runner head mounted for rotation; an abrasive propelling blade mounted on said runner head; means for feeding a stream of abrasive downwardly over the inner end of said blade adjacent the axis of rotation of said runner head, the inner end of said blade having a comparatively short abrasive propelling surface inclining outwardly and rearwardly with respect to the direction of rotation of said runner head, and the outer portion of said blade having a comparatively long abrasive propelling surface inclining outwardly and forwardly with respect to the direction of rotation of said runner head, said long abrasive propelling surface being sufficiently inclined to a radius so that upon rotation of said runner head the abrasive is given an outward acceleration of requisite magnitude to cause it to be discharged in a predetermined direction from said runner head approximately 360 degrees from the point of feeding of said stream of abrasive to said blade.

2. In an abrading apparatus, a runner head mounted for rotation; an abrasive propelling blade mounted on said runner head, said blade terminating short of the axis of rotation of said runner head, whereby the inner edge of said blade generates a surface of revolution; means for feeding a stream of abrasive downwardly over said inner edge of said blade adjacent the axis of rotation of said runner head when said blade is moving through a predetermined portion of each revolution; the inner portion of said blade having a comparatively short abrasive propelling surface inclining outwardly and rearwardly with respect to the direction of rotation of said runner head, and the outer portion of said blade having an abrasive propelling surface inclining outwardly and forwardly with respect to the direction of rotation of said runner head, said outer portion being a plurality of times longer than said inner portion and being so inclined to a radius that movement of the abrasive over said blade consumes a sufficiently long period of time to allow said runner head to turn substantially a full revolution from the time of pick-up to the time of discharge of the abrasive from the runner head.

3. In an abrading apparatus, a runner head mounted for rotation; an abrasive propelling blade mounted on said runner head; means for

- feeding a stream of abrasive over the inner end of said blade adjacent the axis of rotation of said runner head; the inner end of said blade having a comparatively short primary abrasive propelling surface inclining outwardly and rearwardly with respect to the direction of rotation of said runner head, and the outer portion of said blade having a comparatively long secondary abrasive propelling surface inclining outwardly and forwardly 10 with respect to the direction of rotation of said runner head at an angle to a radius sufficiently great to effect outward acceleration of the abrasive over the blade at a rate sufficiently lower than that of a radial blade to effect discharge of the abrasive from the runner head in a predetermined direction angularly remote from the point of feeding of said abrasive stream to said blade, said primary and secondary abrasive propelling surfaces merging into each other so as 20 to provide an abrasive pocket for gathering the abrasive subsequent to pick up but prior to discharge thereof over said secondary surface.
4. The abrading apparatus set forth in claim 3, wherein said primary and secondary abrasive propelling surfaces merge into each other along a curved surface.
5. In an abrading apparatus, a rotor, at least one outwardly extending guideway provided on said rotor, said guideway being open at its outer end, an abrasive propelling blade mounted for sliding movement in said guideway, and means for releasably locking said blade against outward displacement in said guideway comprising a ring-like element mounted for sliding movement adjacent the periphery of said rotor in a direction parallel to the axis of rotation of said rotor, said element being movable into the path of outward movement of said blade and engageable therewith, for locking said blade against outward movement.
- 40 6. The apparatus set forth in claim 5, wherein said rotor is of disc-like form and said element slidably cooperates with the periphery thereof.
7. The apparatus set forth in claim 5, together with means for locking said element against axial movement when said blade is engaged therewith.
8. In an abrading apparatus, a rotor, at least one outwardly extending guideway provided on said rotor, said guideway being open at its outer end, an abrasive propelling blade mounted for sliding movement in said guideway, said blade having an inclined abutment face provided on its outer end, means for releasably locking said blade against outward displacement in said guideway, comprising a ring mounted for axial sliding movement on the periphery of said rotor and having an inclined surface engageable with said inclined abutment face of said blade.
- 55 9. The apparatus set forth in claim 8, wherein said ring is provided with a surface disposed at an acute angle to said inclined surface and is engageable with a side portion of said blade whereby said ring is locked against axial movement.
10. In an abrading apparatus, a rotor member having a plurality of outwardly slidable blades mounted thereon, said rotor member having a plurality of bearing-forming projections provided on the periphery thereof, and a locking ring member mounted for axial sliding movement on said projections into and out of locking cooperation with said blades, said projections spacing said ring member from the periphery of said rotor member for preventing abrasive from becoming wedged therebetween.
- 70 75 11. The apparatus set forth in claim 10, where-

in at least one of said members is provided with a plurality of reversely inclined abrasive baffle faces for preventing abrasive from freely rebounding through the space between said rotor member and said ring member.

12. In an abrading apparatus, a rotor mounted for rotation about a substantially horizontal axis, said rotor having a plurality of blades thereon terminating short of the axis of rotation of said rotor to define a central abrasive admitting space, a stationarily supported abrasive feeding device projecting into said space and operable to feed abrasive over the inner ends of said blades, said device comprising a hollow member of generally cylindrical form disposed closely adjacent the inner ends of said blades and having a peripheral opening located in the lower side thereof and being of a width substantially equal to the width of the inner ends of said blades for delivering abrasive thereover, and a conduit disposed within said feeding device and extending substantially diagonally downwardly and being in communication with said peripheral opening, and means for feeding abrasive to said conduit, the outer surface of said feeding device, forwardly of said peripheral opening, being provided with a plurality of angular rebound surfaces for rebounding back toward said peripheral opening any abrasive that may be improperly picked up by the inner ends of said blades, each of said surfaces being disposed at an obtuse angle with respect to a radial line passing through said surface, said obtuse angles facing rearwardly with respect to the direction of rotation of said rotor.

13. In an abrading apparatus, a rotor mounted for rotation about a substantially horizontal axis; said rotor having a plurality of blades thereon terminating short of the axis of rotation of said rotor to define a central abrasive admitting space; a stationarily supported abrasive feeding device projecting into said space and operable to feed abrasive over the inner ends of said blades, said device comprising a hollow member of generally cylindrical form disposed closely adjacent the inner ends of said blades and having a peripheral opening located in the lower side thereof and being of a width substantially equal to the width of the inner ends of said blades for delivering abrasive thereover; a conduit disposed within said feeding device and extending substantially diagonally downwardly and in communication with said peripheral opening; and means for feeding abrasive to said conduit; said blades being provided with a comparatively long, smooth and straight abrasive propelling surface for smoothly and continuously accelerating the abrasive, said abrasive propelling surface inclining outwardly and forwardly with respect to the direction of rotation of said runner head and being sufficiently inclined to a radius to effect outward acceleration of the abrasive of requisite magnitude to cause it to be discharged in a predetermined direction approximately 360 degrees from the point of feeding of abrasive to said blade.

14. In an abrading apparatus, a rotor mounted for rotation, said rotor having at least one abrasive propelling blade mounted thereon, said blade having an abrasive propelling surface inclining outwardly and forwardly with respect to the direction of rotation of said rotor and having an abrasive gathering pocket at its inner end, means for feeding abrasive over the inner end of said blade, and a baffle spaced from the abrasive propelling surface of said blade adjacent said abra-

sive gathering pocket, for preventing abrasive from being improperly fed to said blade.

15. In an abrading apparatus, a disc-like runner head mounted for rotation, an outwardly extending guideway provided on said head, an abrasive propelling blade mounted for sliding movement in said guideway, means for releasably locking said blade against outward movement in said guideway, said blade having a base portion of considerable area designed to seat against said head when said blade is in place in said guideway, said base being disposed at slightly less than a right angle to said abrasive propelling surface and sufficient spacing being provided between said blade and said guideway whereby when said apparatus is placed in operation and said blade is placed under load said blade will be disposed in a position with its abrasive propelling surface substantially normal to said runner head.

20. 16. An abrasive propelling blade for use in the rotor of a centrifugal abrading apparatus comprising a member having a comparatively long, substantially straight abrasive propelling surface at its outer end, a short abrasive pick-up surface located at its inner end and disposed at an angle greater than 45° and less than 100° with

respect to said abrasive propelling surface, and a surface portion of concave formation between said surfaces and merging them together.

17. The abrading apparatus described in claim 2, together with means for adjustably securing said blades to said runner head with said abrasive propelling surface disposed at various selected inclinations on said runner head, for varying the accelerating action thereof upon the abrasive.

18. In an abrading apparatus, a disc-like rotor carried by a shaft mounted for rotation, a disc detachably secured to one face of said rotor and operable to protect the entire face thereof against abrasion, said disc having a plurality of outwardly extending slots therein and cooperating with the face of said rotor to define guideways for a plurality of outwardly extending abrasive propelling blades, said rotor forming the bottoms of said guideways and adapted to be protected against abrasion by said blades, and wherein the walls of said slots form the sides of said guideways, the inner ends of said slots being closed to limit inward movement of said blades.

WALTER L. KEEFER.
